OR D 17,772

DESIGN.

—o—

A. L. HALLIDAY.

CARPET.

No. 17,772.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,772, dated October 11, 1887.

Application filed September 8, 1887. Serial No. 949,157. Term of patent 33 years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is composed of a body part, A, and a border, B.

The body design A consists of a mass of 20 small ornamental figures of a geometrical character, varying in size and shape. Some of the larger of these ornamental figures are grouped together, so as to form irregular and inconspicuous diamond and other shapes. Between the diamond-shaped groups the ornamental 25 figures are smaller in character. Series of broken lines run lengthwise of and across the design, making a partial block-work.

The border has an inner ornamented mar-

gin. On this margin as a base, and extending nearly across the entire width of the border, stand triangular forms cut away at the lower angles and capped at the top. These triangular forms overlie one another, forming smaller triangular forms where they overlie. The smaller triangular forms inclose three 35 large circular figures of an ornamental character. The remaining central portion of the larger triangles is covered with a close mass of small ornamental figures resembling the body part of the design. In the spaces between the 40 caps of the larger triangles are large star-shaped figures. The outer part of the border is ornamented chiefly with less prominent lines and circles with a few geometrical forms.

What I claim as new, and desire to secure 45 by Letters Patent, is—

1. In a design for carpets, the body A, substantially as shown.

2. In a design for carpets, the border B, substantially as shown.

3. The design for carpets, consisting of the body A and border B, substantially as shown.

ARTHUR L. HALLIDAY.
